US00D403913S

United States Patent

[19]

DardashtiPatent Number: Des. 403,913*Date of Patent: Jan. 12, 1999*[54] STORAGE ASSEMBLY

[76] Inventor: Shahriar Dardashti, c/o Atlantic, Inc.,
P.O. Box 2399, Santa Fe Springs, Calif.
90670

[] Term: 14 Years

[21] Appl. No.: 77,191

[22] Filed: Sep. 29, 1997
